US0D1067711S

(12) **United States Design Patent** (10) **Patent No.:** **US D1,067,711 S**
(45) **Date of Patent:** **** Mar. 25, 2025**

(54) **FOOD WARMER**

(71) Applicant: **Wellfine Silicone Products Co., Ltd.,**
Dongguan (CN)

(72) Inventors: **Feng Liu**, Dongguan (CN); **Shihao Wang**, Dongguan (CN)

(73) Assignee: **Wellfine Silicone Products Co., Ltd.,**
Dongguan (CN)

(**) Term: **15 Years**

(21) Appl. No.: **29/974,771**

(22) Filed: **Nov. 25, 2024**

(30) **Foreign Application Priority Data**

Oct. 29, 2024 (CN) 202430682926.8

(57) **CLAIM**

The ornamental design for a food warmer as shown and described.

DESCRIPTION

FIG. 1 is a front, right and top perspective view of a food warmer, showing our new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of detail 9 in FIG. 2.

The dashed broken lines depict portions of the Food Warmer that form no part of the claimed design. The dot-dash broken lines in FIGS. 2 and 9 depict the boundaries of the enlarged views and form no part of the claimed design.

1 Claim, 9 Drawing Sheets
